CLAIM

The ornamental design for a coin guard face plate, as shown and described.

DESCRIPTION

FIG. 1 is a right-side perspective view (as viewed from the design) showing my new design of a coin guard face plate; FIG. 2 is a left-side perspective view thereof; FIG. 3 is a right, side-elevational view thereof; FIG. 4 is a left, side-elevational view thereof; FIG. 5 is a top plan view thereof; FIG. 6 is a bottom plan view thereof; and, FIG. 7 is a rear elevational view thereof. FIGS. 3-7 are shown on a reduced scale.
